BATTERY TERMINAL CONNECTOR

Orrin H. Thomas, Williamsport, and Robert Elton,
Shenandoah, Pa.

Application December 19, 1946, Serial No. 717,296

4 Claims. (Cl. 173—259)

1

The present invention relates to improvements in connectors for battery terminals or posts, more particularly to a clamp of the split ring or socket type.

As is well-known, battery terminals are subject to corrosive action, and many attempts have been made to design a clamp that will be resistant to such corrosion. However, there are practical and/or manufacturing difficulties involved which must be given consideration, and in many respects, this has made it necessary to compromise between advantageous features of design to make up for the unsuitability or inefficiencies of available materials required to meet the optimum design characteristics.

One general design characteristic of battery connectors is that the clamping jaws of the socket type terminal be of comparatively soft or pliable non-corrosive metal or alloy, in order to afford a certain amount of give or yield in the metal when the connector is clamped around a battery post. It is also desirable, if not necessary, to use a pliable metal for this purpose to insure good contact between the terminal and connector, and to avoid undesirable or excessive corrosion there-between.

A disadvantage in using soft metal for the jaws of the clamp is that they soon become deformed from their original shape in adapting the connector to different size terminals; also, a soft metal has practically no resiliency and will not hold a thread satisfactorily.

For these and other reasons, the trend of the industry has been directed to the use of harder, non-corrosive metals for the socket members of connectors. On the whole, non-corrosive hard metals have not been too satisfactory for this purpose, chiefly because they will not permit the allowance of enough tolerance for the variations in terminal posts, which a commercial connector must provide to meet successfully trade conditions.

For example, many conventional forms of battery terminal connectors are constructed of a one piece ring or socket split on one side only, so that any adjustment obtained in clamping the terminal to the battery post is provided by drawing the open ends towards each other. By this arrangement, it is impractical to construct the connector from a hard metal because the metal fractures when the connector ends are drawn together around the battery post, owing to the lack of resiliency and/or contractibility of hard metal.

There are numerous other objections well known to those skilled in the art which dictate against the general use of metals which are not pliable, even though they possess superior non-corrosive qualities because of their hardness.

It is, therefore, the principal object of the present invention to provide a battery terminal connector which possesses to a large degree the

2

most advantageous features of both soft and hard metals with respect to resisting corrosion, making good contact with the battery post, and being adapted for universal use in connection with present standard batteries.

Another object is the provision of a battery connector, the jaws of which are of soft or pliable metal but are reinforced by a member made of hard non-corrosive metal, the reinforcing member being intimately bonded to the soft metal.

Another object of the invention is the provision of a connector construction embodying an insert, for purposes of reinforcement, and including means for fastening the connector to the battery terminal, said fastening means being protected principally from the corrosive action of the battery solution.

Another object of the invention is the provision of a connector of the socket type split on both sides of center to form opposing halves, laterally expansible, and designed to be drawn together by pressure effected from diametrically opposite positions, whereby a more uniformly distributed gripping force is obtained in clamping the connector to a battery post, thus substantially reducing the likelihood of fracturing the metal composing the connector halves.

A special object is the provision of a connector of the split ring or socket type, in which at least one of the connector halves is adapted to take a screw thread which has durability and is non-corrosive.

A further object is the provision of protective means against corrosion of a screw adapted to engage the above-mentioned screw threads and function as means for fastening the connector to the battery post.

Other objects relating to features of construction, combination of elements and arrangement of parts are either obvious or will manifest themselves as the description proceeds.

For a full and more complete understanding of the invention, reference may be had to the following description and accompanying drawing, 45 wherein:

Figure 1 is a fragmentary side elevation of a connector embodying the invention;

Figure 2 is a section taken on the line 2—2 of Figure 1;

Figure 3 is a fragmentary side elevation showing a modification of Figure 1;

Figure 4 is a section through line 4—4 of Figures 1 and 3; and

Figure 5 is a perspective view of one form of the reinforcing member contemplated by the invention.

Referring to the drawings, more particularly to Figures 1, 2, and 4, wherein is illustrated one form of a battery terminal connector contemplated by the invention, it will be seen that the connector is of the split ring or socket type com-

posed essentially of two jaws or halves 1 and 2, which are split on both sides of center and, when drawn together, form an adjustable clamp. Each of the jaws 1 and 2 has formed in its opposing face a semi-circular tapering recess 3, corresponding to the taper of a battery post (not shown) so that when joined together they define a cylindrical-shaped tapered socket conforming to the shape of the post and making a snug fit therewith.

It will be noted that the halves 1 and 2 are complementary, and are designed to have their opposing faces 4 and 5 on one side of center engage each other. This arrangement affords a pivotal point or surface for the jaw halves when a binding pressure is applied to secure the connector to the battery post, as hereinafter more fully described. The opposing faces 6 and 7 do not meet and, therefore, form a gap which permits relative movement of said faces towards each other when the jaws 1 and 2 are tightened.

The jaw 2 may constitute the cable side of the connector, in which event it is provided with a hub 8 having a central recess adapted to receive the end of a cable 9, which may be secured within said hub in any suitable manner as by welding or the like.

The clamping jaws or halves 1 and 2 may be composed of any suitable soft or pliable, non-corrosive alloy or metal commonly used for battery terminal connectors. In practice, it is the pliability of the metal that is relied upon to permit the bending of the connector jaws about or around the battery post in order to accommodate battery posts differing in diameter sizes. However, it is easy to exceed the elastic limit of such metals and the jaws become set or deformed so that in removing the connector from the battery post, it is necessary to use a screw driver or similar tool to pry the jaws apart. Frequently, this results in permanent damage to the battery, as well as making its removal difficult. It is, therefore, obvious that the ideal connector is one which will fit a variety of battery posts, make good contact, retain or assume its original shape, and is easy to remove. The present invention provides these characteristics through the novel construction presently described.

Looking at Figure 1, it will be seen that the cable half 2 of the connector is provided with a U-shaped reinforcing insert, referred to generally by the reference character 11, and composed of a hard, non-corrosive metal, such as stainless steel. The insert 11 is cast in any suitable way in the halves 1 and 2, and one form may comprise a bar piece 12 having posts 13 and 14 formed on the extremities thereof, each of said posts being hollow and provided with internal threads adapted to engage suitable threads formed on cap screws 15, also of stainless steel. The principal function of the insert is to reinforce the connector halves 1 and 2 so that they will possess a substantial degree of tension when clamped around the battery post.

The connector half 1 is provided with apertures 16 in axial alignment with the recesses of the hollow posts 13 and 14 of the insert 11; said apertures being unthreaded and merely bushed with suitable non-corrosive bushings 17 and 18, such as "phenolite." It will be noted that the posts 13 and 14 are of unequal length, the post 13 extending flush with the face 5, and the post 14 ending below the face 7, thus leaving a recess 19 formed above the end of said post 14 and opening onto the face 7. The lengths of the

bushings 17 and 18 are such as to complement the lengths of the posts 13 and 14, i. e., the bushing 17 merely extends flush with the jaw face 4, and the bushing 18 projects beyond the jaw face 6 sufficiently to bridge the gap between the faces 6 and 7, and extend into the recess 19, when said jaw faces 6 and 7 are moved towards each other in tightening the connector on the battery post. This arrangement of the bushings is a feature in making the connector acid proof.

If desired, the insert 11 may be greatly simplified for the connector half 1, as shown in Figure 1. The insert in this latter instance may comprise a flat, relatively narrow piece 10 of metal of a non-corrosive alloy, preferably stainless steel, imbedded lengthwise of the connector half. It is obvious that this form of insert makes it possible to simplify the whole clamping means for securing the connector to the battery post, and at the same time provides sufficient reinforcement, which is manifested by the connector halves substantially retaining their initial shapes, when the binding pressure is relieved, although the halves may be drawn tightly around the battery post.

A more rugged form of connector is disclosed in the modification illustrated in Figure 3. In this modification, each half of the connector is provided with inserts 25 and 29 that are generally similar to each other. The insert 25, which is cast in the half 1, comprises a bar piece 28 having posts 26 and 27 provided with an opening throughout their lengths, and said opening is not threaded. The insert 29 has hollow posts 30 and 31 which are internally threaded.

It will be noted that the posts 30, 31 and 26, 27 are of the same length but do not extend flush with the opposing faces 4, 5 and 6, 7. The space above the ends of the posts is bored to a larger diameter than that of the posts 30, 31 and 26, 27, and sleeve bushings 21 and 22 are inserted within the apertures thus formed. Since the opposing faces 4 and 5 of the connector halves 1 and 2 are designed to contact each other, the length of the bushing 21 may be substantially the combined length of the aligned apertures for accommodating the bushing 21. On the other hand, there is a gap between the faces 6 and 7, but the bushing 22 is shorter than the over-all length of the recesses in the faces 6 and 7. Consequently, when the bushing 22 is inserted, there is a space 23 left above the end of the bushing 22 which accommodates said bushing upon the closure of the gap between the faces 6 and 7 when the cap screws 15 are tightened.

It will be understood from the above description that the bushings 21 and 22 constitute protective means against corrosion for both the inserts 29 and 25; also for the cap screws 15. It will also be appreciated that the posts 26 and 27 of the insert 25, not being threaded, merely constitute journals for the cap screws 15 passing therethrough.

It is obvious from the foregoing description that in fastening the terminal connector to the battery post, the cap screws 15 are loosened sufficiently to permit the separation of the terminal jaws 1 and 2 so as to receive or enclose the battery post. When the battery post has been inserted within the socket formed by the connector halves, the cap screw 15 passing through the aligned openings of the connector faces 4 and 5 is first tightened in order to bring the faces 4 and 5 into tight contact with each other. The cap screw 15 on the gap side of the connector is

then tightened, thus drawing the faces 6 and 7 towards each other. This produces a binding pressure around the battery post on both sides of center, and insures good contact between the connector and the battery post. Since the connector halves 1 and 2 are composed of a pliable, non-corrosive metal, and since the reinforcing inserts are composed of a hard, non-corrosive metal; and further, since the cap screws for tightening the clamp are protected from corrosion by suitable bushings, the complete connector structure is made acid proof. At the same time, the connection halves are sufficiently resilient because of the reinforcing inserts as practically to resist serious deformation.

As previously stated, to obtain the most effective connector, it is a compromise between a construction employing soft pliable metals, which provide a wide fitting range with respect to the sizes of battery posts but possess objectionable features, and the use of hard, non-corrosive metals which allow but small tolerances in the diameter variations of the battery posts. The design of the present connector combines the best features of prior art connectors into a simple construction.

While certain preferred embodiments of the invention are hereinbefore set forth, it is to be clearly understood that the invention is not to be limited to the exact construction illustrated and described because various modifications of the details may be provided in putting the invention into practice within the purview of the appended claims.

What is claimed is:

1. A battery terminal connector, comprising a pair of coacting sections, each of said sections including a jaw member formed of soft, non-corrosive metal and having a semi-circular recess, a U-shaped reinforcing insert embedded in one of said jaw members and having a pair of hollow posts, a second U-shaped insert embedded in the other of the jaw members and having a pair of threaded sockets, said first-mentioned jaw member having recesses concentric with the adjacent hollow posts, said second-mentioned jaw member having recesses concentric with said threaded sockets and in alignment with said recesses in said first mentioned jaw member, a first bushing extending into one of said recesses in said first mentioned jaw member and extending into one of said recesses in said second mentioned jaw member, a second bushing extending into the other of the recesses in said first mentioned jaw member and extending into the other of the recesses in said second mentioned jaw member, and a pair of screws protruded through said posts and bushings and engageable in said threaded sockets.

2. A battery terminal connector comprising a pair of sections fabricated of soft metal arranged in face to face relation and the meeting face of each of said sections being provided with a recess conforming to the shape of a battery post; a hard metal insert embedded in each of said sections, said insert comprising a pair of spaced hollow posts; the adjacent ends of said posts being spaced from the meeting face of their respective sections and one pair of posts being internally threaded; each of said sections being provided with a pair of spaced apertures extending inwardly from the meeting face thereof; a pair of bushings projecting into the apertures in each of said sections and in communication with the adjacent ends of the adjacent posts; and a

pair of threaded elements protruding through the other pair of posts and through said bushings and in threaded engagement with said one pair of posts.

3. A battery terminal connector comprising a pair of sections fabricated of soft metal arranged in face to face relation and the meeting face of each of said sections being provided with a recess conforming to the shape of a battery post; a hard metal insert embedded in each of said sections, said insert comprising a pair of spaced hollow posts; the adjacent ends of said posts being spaced from the meeting face of their respective sections and one pair of posts being internally threaded; each of said sections being provided with a pair of spaced apertures extending inwardly from the meeting face thereof; a pair of bushings projecting into the apertures in each of said sections and in communication with the adjacent ends of the adjacent posts; one of said bushings being shorter than the other; and a pair of threaded elements protruding through the other pair of posts and through said bushings and in threaded engagement with said one pair of posts.

4. A battery terminal connector comprising a pair of sections fabricated of soft metal arranged in face to face relation and the meeting face of each of said sections being provided with a recess to form a pair of projections and one of said projections being shorter than the other and the longer projections being in contacting relation with respect to each other and the shorter projections being spaced with respect to each other and said recesses conforming to the shape of a battery post; a hard metal insert embedded in each of said sections, said insert comprising a pair of spaced hollow posts extending into said projections; the adjacent ends of said posts being spaced from the meeting face of their respective sections and one pair of posts being internally threaded; each of said longer projections and each of said shorter projections being provided with an aperture extending inwardly from the meeting face of its respective section; a first bushing projecting into the apertures in said longer projections and in communication with the adjacent ends of the adjacent posts; a second bushing projecting into the apertures in said shorter projections and in communication with the adjacent ends of the adjacent posts; and a pair of threaded elements protruding through the other pair of posts and through said bushings and in threaded engagement with said one pair of posts; said bushings being adapted to prevent corrosion of said inserts and said pair of threaded elements.
